United States Patent Office

Des. 193,060
Patented June 19, 1962

193,060

DESK

Clifford L. Rowse, P.O. Box 471, Richmond, Tex.

Filed July 17, 1961, Ser. No. 65,958

Term of patent 14 years

(Cl. D33—7)

Fig. 3

Fig. 4

FIG. 1 is a front isometric view of a desk, showing my new design;

FIG. 2 is a rear isometric view thereof;

FIG. 3 is a rear elevational view thereof; and

FIG. 4 is an elevational view of the side opposite that shown in FIG. 1.

I claim:

The ornamental design for a desk, substantially as shown.
